A. BAGAMERY

SAFETY CIGAR HOLDER

Filed March 6, 1926

Fig. -1.

UNITED STATES PATENT OFFICE.

ALEXANDER BAGAMERY, OF SOUTH RIVER, NEW JERSEY.

SAFETY CIGAR HOLDER.

Application filed March 6, 1926. Serial No. 82,785.

This invention relates generally to cigars, the invention having more particular reference to a novel type of receiver to hold the ashes from the said cigar.

5 The invention has for an object the provision of an improved receiver for cigar ashes adapted to be placed over the lighted end of the cigar, so as to prevent the ashes from the said cigar from causing damage by 10 dropping therefrom.

For further comprehension of the invention, and of the objects and advantages thereof, reference will be had to the following description and accompanying drawing, 15 and to the appended claims in which the various novel features of the invention are more particularly set forth.

Fig. 1 of the drawing, is a perspective view of my improved receiver for cigar ashes.

20 Fig. 2, is a longitudinal central sectional view thereof.

Fig. 3 is an enlarged fragmentary view thereof, showing in particular the cap as used in connection with my improved device.

Fig. 4 is a longitudinal central sectional view, showing a modification of my improved device.

As here embodied my improved receiver 30 for holding cigar ashes comprises a cigar holder 10, provided with a tip 11, an aperture 12, or cavity, and an axial aperture 13, the above mentioned construction being such as common to cigar holders used by 35 smokers to hold a cigar 14, when it is desired to smoke the said cigar 14. The cigar holder 10, is also provided with an adjustable member 15, a set screw, or the like, such as will hold the said cigar 14 firmly 40 in place in the cigar holder 10, which is further provided with a threaded outer extremity 16, to accommodate the inner extremity 17 of the receiver 18, which is threadedly attached thereto, and comprises a hollow cylindrical member, having a cap 19, hinged to the outer extremity 20, of the receiver 18, as at 21, by a pin 22. The said cap 19 is normally held in a closed position by the spring 23, having extremities 24 and 45 25, which hold the said cap 19 in the heretofore mentioned position. The said receiver 18, and the said cap 19 are provided with a plurality of apertures 26.

Referring in particular to Fig. 4 of the 50 accompanying drawing, in which I have shown a modification of my improved de-

vice. The cap 19 is provided with an extended element 27, which has pivotally attached thereto as at 28, one extremity of a rod 29, which is pivotally attached at its other extremity, as at 30 to a lever 31 which is pivotally attached at one extremity, as at 32, to the said inner extremity 17, of the receiver 18. The above mentioned construction being such as will permit the cap 19 to 55 be hinged open, by pressing the said lever 31, and is enclosed in a longitudinal hump 18' of casing 18.

It will be understood that my improved receiver for cigar ashes, as above described, 70 is especially adapted for holding the said cigar ashes, until such a time as the said cap 19 is opened, and that the said apertures 26, are preferably of small area, so as to permit air to enter the said receiver 18, but to prevent the cigar ashes from falling through the said apertures 26.

Having thus described my invention, what I claim as new and desire to protect by Letters Patent of the United States is as follows:—

1. A receiver for cigar ashes adapted to be placed over the lighted end of a cigar, to prevent the ashes of the said cigar from dropping therefrom, and a cap hinged to 85 said receiver for closing the end thereof, a spring for normally holding said cap in tight fitting relation on the end of said receiver and a system of levers for opening said cap against the pressure of said spring. 90

2. In a device of the class described, a receiver comprising a hollow cylindrical member having at its outer extremity a cap hinged thereto by a pin, said cap normally held in a closed position by a spring, said 95 receiver, at its inner extremity, threadedly attached to a cigar holder, said hollow cylindrical member, and said cap provided with a plurality of apertures, and means comprising a lever operatively mounted on said cigar 100 holder for opening said cap against the tension of said spring.

3. In a device of the class described, a hollow cylindrical member, a cap hinged to the outer extremity of said cylindrical member, an extension on said cap extending upwardly therefrom, a lever pivotally mounted on the opposite extremity of said receiver, and a rod pivotally attached at one end to said extension and at the other end to said lever and adapted to open said cap when said lever is pressed. 110

4. A receiver for holding cigar ashes comprising a holder provided with a tip, an axial aperture and a cavity to hold a cigar, an adjustable member for holding said cigar 5 firmly in place in said holder, external threads on the end of said holder, a receiver screw threaded on said cigar holder, a cap hinged to the end of said receiver, a spring 10 for normally holding said cap in closed position, said cap and receiver being provided with a plurality of apertures of a size sufficiently large to permit the inlet of air and small enough to prevent the passage of ash therethrough, a projection extending upwardly from said cap, an operating lever 15 pivotally mounted on said receiver, and a rod pivotally attached at one end to said projection and at the other end to said operating lever for opening said cap against the action of said spring when said lever is 20 pressed.

In testimony whereof I have affixed my signature.

ALEX BAGAMERY.
